UNITED STATES PATENT OFFICE.

CLARENCE RUNYAN, OF AURORA, INDIANA.

COMB CLEANER.

1,422,788.

Specification of Letters Patent. Patented July 11, 1922.

Application filed August 30, 1921. Serial No. 496,856.

To all whom it may concern:

Be it known that I, CLARENCE RUNYAN, a citizen of the United States, residing at Aurora, in the county of Dearborn and State 5 of Indiana, have invented new and useful Improvements in Comb Cleaners, of which the following is a specification.

This invention comprehends the provision of a device designed for cleaning hair combs 10 or the like, by means of which fine particles collected between the teeth of the comb, such as dandruff, grease, dirt or the like can be quickly and easily removed.

The invention aims to provide a device of 15 this character which is very simple in construction, so that it may be manufactured and sold at a very nominal cost, the device embodying threads arranged in spaced parallel relation across the open side of a frame 20 like member, the threads being associated with the frame in a manner whereby they can be readily and quickly replaced by any one when the occasion requires.

The nature and advantages of the invention 25 will be better understood when the following detail description is read in connection with the accompanying drawings, the invention residing in the construction, combination and arrangement of parts as 30 claimed.

In the drawing forming part of this application, like numerals of reference indicate similar parts in the several views, and wherein:

35 Figure 1 is a plan view of the device forming the subject matter of the invention.

Figure 2 is a side elevation.

Figure 3 is an end elevation.

40 Figure 4 is a sectional view taken on line 4—4 of Figure 1, the strands being omitted.

Figure 5 is a sectional view through the handle.

Figure 6 is a detail view of one end of the handle.

45 Referring to the drawing in detail, the device forming the subject matter of the invention embodies a substantially U-shaped frame indicated at 10, while projecting from the free edge of the parallel end members

50 12 are outwardly extended lugs or fingers 13 about which the thread 14 is passed in a manner to provide a plurality of spaced

parallel strands which may be more or less closely associated as the occasion may require. One of the end walls 11 is provided 55 with notches 13, these notches defining extensions 14 about which the free terminals of the threads are tied as illustrated. The opposite end wall 11 is provided with spaced slots 15 which receive the bendable tongues 60 16 projecting from the adjacent end of a handle 18. After the tongues are passed through the slots they are bent against the end wall 11 to hold the handle fixed relatively to the frame as will be readily understood. The handle is preferably of U-shaped formation in cross section, although it may vary in size and configuration without departing from the spirit of the invention. The device is very simple in construction 70 and can be manufactured and sold at a very nominal cost, by use of the device, the comb can be quickly and easily cleaned without soiling the fingers.

While it is believed that from the foregoing description the nature and advantages of the invention will be readily apparent, I desire to have it understood that I do not limit myself to what is herein shown and described and that such changes may be 75 80 resorted to when desired as fall within the scope of what is claimed.

What I claim is:

A comb cleaner comprising a substantially U-shaped frame, fingers projecting from the 85 upper edge of the parallel end walls of said frame, one end wall having notches in its opposed side edges, a thread passed about said fingers in a manner to provide spaced parallel strands extended across the open 90 end of the frame, with the terminals of said thread in said notches, the opposite end wall of the frame having parallel slots, a handle formed from a single piece of material, said handle being of substantially U-shaped formation in cross section, bendable tongues 95 projecting from the opposed sides of the handle and adapted to be passed through said slots and subsequently bent against the adjacent end wall for holding said handle 100 and frame fixed relatively.

In testimony whereof I affix my signature.

CLARENCE RUNYAN.
